CLAIM

The ornamental design for a flush ceiling light, as shown and described.

DESCRIPTION

FIG. 1 is a bottom perspective view of a flush ceiling light showing our new design;

FIG. 2 is a top perspective view thereof;

FIG. 3 is a bottom view thereof;

FIG. 4 is a front view thereof, the back view being identical thereto;

FIG. 5 is a right side view thereof, the left side view being identical thereto;

FIG. 6 is a top view thereof;

FIG. 7 is a sectional view thereof, taken along the 7-7 line of FIG. 3;

FIG. 8 is a sectional view thereof, taken along the 8-8 line of FIG. 6;

FIG. 9 is a partial enlarged view showing section 9-9 of FIG. 8; and,

FIG. 10 is a partial enlarged view showing section 10-10 of FIG. 7.

In the drawings, the oblique line shading in FIGS. 7 through 10 represents transparency.

The broken line portions in the drawings represent environmental subject matter only and form no part of the claimed design.
